UNITED STATES PATENT OFFICE.

MARTIN BARRI, OF LOWELL, MASSACHUSETTS, ASSIGNOR TO LAMSON CONSOLIDATED STORE SERVICE COMPANY, OF NEWARK, NEW JERSEY.

PNEUMATIC-DESPATCH-TUBE APPARATUS.

SPECIFICATION forming part of Letters Patent No. 681,013, dated August 20, 1901.

Application filed August 25, 1900. Serial No. 28,008. (No model.)

To all whom it may concern:

Be it known that I, MARTIN BARRI, of Lowell, in the county of Middlesex and State of Massachusetts, have invented certain new and useful Improvements in Pneumatic-Despatch-Tube Apparatus, of which the following is a specification.

My invention relates to improvements in pneumatic - despatch apparatus, and especially to a pressure system wherein the carriers are driven from end to end of the same tube in either direction by air-pressure behind the carriers.

The object of my invention is to cut off the air-pressure upon the discharge of the carrier at the opposite end of the line, so that the pressure is used only when carriers are being despatched. This object is accomplished by mechanism so timed in operation that upon the carrier being discharged the pressure is cut off.

My invention consists of certain novel features hereinafter described, and particularly pointed out in the claims.

In the accompanying drawings, which illustrate a construction embodying my invention, Figure 1 is a side view illustrating the tube through which the carriers are sent in either direction with the despatching and receiving terminal at each end. Fig. 2 is a top plan view of the despatching mechanism with the cover removed. Fig. 3 is a longitudinal central sectional view of the despatching mechanism and of the transmission-tube. Fig. 4 is a similar view to Fig. 3, but showing the mechanism in position after the carrier has been inserted and the air-pressure admitted to drive the carrier to the opposite end of the tube. Fig. 5 is an end view with the casing partly removed. Fig. 6 is a view similar to Fig. 5 and showing certain parts in section. Fig. 7 is a side view, partly in section, and showing certain operating mechanism for admitting air-pressure to drive the carrier from end to end of the tube.

Like letters of reference refer to like parts throughout the several views.

When it is desired to despatch a carrier, it is inserted into the terminal at the inlet A, Figs. 1, 3, and 4, and passes down through the opening C' of the valve-box C into the

despatch-tube B. The valve C² is then closed by rolling it to the position shown in dotted lines, Fig. 3, and full lines, Fig. 4. The valve C² is provided with a series of pins C³, which extend into suitable openings in the carriage D, and is guided in said carriage as it raises and lowers, due to the admission and non-admission of air-pressure for driving the carriers. This carriage D is provided with rollers D', which roll along the guideways E. As shown in Figs. 3 and 4, the links D², pivoted to the rollers D', are pivotally connected at D³ to oppositely-arranged rocking arms D⁴, which extend upwardly and are secured fast on the shaft D⁵, passing through the valve-box C. This valve-box is provided with a closed pocket D⁶, through which the shaft D⁵ passes, and on said shaft and projecting into the closed pocket D⁶ is a lever F, and bearing against the lower end of this lever is another forked lever G, the upper end of which is mounted loosely on the shaft G', journaled in the upright supports G², secured to the plate G³, and said lever passes down through suitable opening in said plate. The shaft G' extends outwardly on one side and is provided with a handle G⁴, for a purpose hereinafter described. On this shaft G' is securely fastened the forked lever G⁵, provided at its outer end with the roll G⁶, mounted on the pivot G⁷, and against the inner end of said lever G⁵ bears the lip G⁸, Fig. 7, projecting outwardly from the lever G. This lip G⁸ on the lever G is held in contact with the lever G⁵ by the spring G⁹ around the shaft G⁴ and having one end secured to said shaft and the other end bearing against the lever G and holding the lip G⁸ in contact with the lever G⁵ at all times, as shown in Figs. 3, 4, and 7. In order to close the valve C², the handle G⁴ is moved forward toward the left from the position shown in Fig. 3, moving with it the shaft G', to which the lever G⁵ is secured, and through the medium of the spring G⁹ the lever G and lever F and the valve C² are moved into the position shown in full lines, Fig. 4, thereby closing the opening C' in the valve-box C which communicates with the despatch-tube B. Located within the pocket J and secured to the plate G³ is a plate K, provided with a hub K', within which is

mounted the plunger K^2 , provided at its upper end with a flange K^3 , against which the roll G^6 on the lever G^5 bears. Within the pocket J is mounted the piston-plunger L , held in its raised position, Fig. 3, by the spring D^2 , and this plunger L is provided with a hollow stem L^3 , to which the valve L^4 is secured by suitable nuts L^5 and the lower one of which is provided with suitable air-openings L^6 , 10 communicating with the pocket M of the valve-box C . The spring L^7 tends to keep the plunger K^2 in its upper position. (Shown in Fig. 3.) The flange L^3 on the stem L^3 limits the downward movement of the plunger K^2 in the pocket J . The plunger K^2 is provided with a series of radial openings K^4 and with a groove K^5 on the outer periphery of said plunger.

M' is a plate covering the bottom of the valve-box C , to which the air-pressure-supply pipe M^2 is connected and which communicates with the pocket M . To this plate is also secured the despatch-tube B for the transmission of the carriers. The air-supply pipe M^2 extends between the terminals and at a convenient point is connected to an air-tank m^3 by the pipe M^4 under suitable air-pressure, and air is supplied by a suitable air-pump through the pipe m^5 . Extending upwardly from the plate G^3 and secured thereto is a curved portion N of the terminal, having an opening N' for the discharge of the carriers into a suitable receptacle. Communicating with the valve-box C is a pipe H , which at its opposite end is in communication with the piston-chamber H' , and within said piston-chamber is located the piston H^2 , having a suitable piston-rod H^3 , which at its outer end without the cylinder is connected by the 25 pin H^4 , working in a slot in the arm H^5 , secured fast on the shaft H^6 , mounted in a suitable support H^7 , and on the opposite end of said shaft H^6 and fast thereto is another arm H^8 , having journaled at its end the roll H^9 . On the bottom of said support H^7 there is pivoted the spring-catch O , normally held in position by the light spring P to engage with the flange K^3 when the plunger K^2 is depressed by the lever G^5 . Mounted on the arm H^8 is 30 an adjustable set-screw P' , adapted to engage the spring-catch O and move it away from engagement with the flange K^3 , so that the plunger K^2 may rise from the position shown in Fig. 4 to that shown in Fig. 3 and close the valve L^4 . In one end of the cylinder H' is an opening P^2 , the area of which may be increased or diminished by adjusting the screw P^3 , thus controlling the time in which the air is allowed to escape from the cylinder 35 H' as the piston H^2 moves from the right to the left by the air-pressure from the pipe H . When the piston H^2 reaches the position shown in Fig. 4, the arm H^5 is moved from the position shown in Fig. 3 to that shown in Fig. 4, and by its connection with the arm H^8 through the shaft H^6 moves the spring-catch O from its engagement with the flange K^3 to

the position shown in Fig. 4, and the spring L^7 , being under tension, throws the plunger K^2 upwardly, which, engaging with the arm H^5 , forces it upwardly and throws the arm H^5 inwardly, and with it the piston-rod H^3 and piston H^2 , to the position shown in Fig. 3, and the suction exerted by the piston in its movement draws inwardly the hollow air-inlet valve Q , and through said valve the air enters and passes through the openings Q' into the piston-chamber H' and fills said chamber with air. Upon the next operation of despatching a carrier the valve Q moves from its open position (shown in Fig. 3) to its closed position, (shown in Fig. 4,) so that as the piston H^2 moves toward the left all the air in front of the piston H^2 must pass out through the adjustable restricted opening P^2 . When the piston is moved toward the right, the air-valve Q moves to the position shown in Fig. 3 and again supplies said chamber H' with air. When the plunger K^2 has been depressed by moving the lever G^4 , as previously described, the openings K^4 move downwardly, Fig. 4, and open into the space K^6 above the plunger L , and the air-pressure passing up from the pipe M^2 through the openings L^6 and through the hollow stem L^3 pass out through said openings K^4 into the space K^6 , and by reason of the piston-plunger L being of greater area than the valve L^4 the plunger L moves downwardly and forces the air in the pocket J out through the opening L^9 and opens the valve L^4 to the position shown in Fig. 4, and the pressure passes through the opening L^{10} into the valve-box C and from there into the tube B , through which the carrier is driven, and at the same time acts on the bottom of the valve C^2 and raises it up and holds it against its seat A' , as shown in Fig. 4. At the same time the air passes upwardly around the closed pocket D^6 and into the pipe H and passes into the piston-chamber H' and forces the piston toward the left and operates the connecting mechanism, as hereinbefore described, to allow the closing of the valve L^4 , as above described, after the carrier has reached the opposite end of the line, and when the spring-catch O is released in the manner above described the plunger K^2 rises from the position shown in Fig. 4 to that shown in Fig. 3, which brings the openings K^4 up into the hub K' to close the communication between the pipe M^2 and the chamber K^6 above the piston-plunger L , and the air-pressure in said chamber passes through the groove K^5 up and out above the hub K' , and the spring L^8 , acting on the plunger L , raises said piston-plunger to the position shown in Fig. 3, and the pressure acting on the valve L^4 closes said valve, and the pressure being relieved from below the valve C^2 said valve drops onto its carriage D , and the spring R on the shaft D^5 moves said valve to its open position, (shown in Fig. 3,) when the apparatus is in condition for the despatch of another carrier. When the com-

pressed air from the tube M^2 has passed up during the opening of the valve L^4 into the pipe H , it drives the piston H^2 toward the left from the position shown in Fig. 3, and the rapidity of the movement of the piston depends upon the area of the small opening at the left-hand end of the cylinder, so that in a long line the screw P^3 would be adjusted so as to make the opening P^2 small in order to retard the egress of the air, while in a short line the screw P^3 would be adjusted to increase the area of the opening P^2 to allow the air to pass out rapidly, so that by this adjustable arrangement the flow of air from the cylinder H^1 can be controlled to allow the carriers to travel any predetermined distance. After a carrier has passed out at the opposite end of the line the piston H^2 reaches the position shown in Fig. 4 and operates the mechanism hereinbefore described to close the valve L^4 and shut off the air-pressure, thus providing for the use of the air-pressure only during the transmission of carriers.

The operation is as follows: A carrier is dropped into the inlet A at the right-hand end of Fig. 1 and passes down through the opening C' in the valve-box C into the despatch-tube B , and the handle G^4 is then moved to the left from the position shown in Fig. 3 to that shown in Fig. 4 and moves the valve C^2 across the mouth of the tube B , as previously described. This movement of closing the valve also pushes down the lever G^5 , fast on the shaft G' , and the lever G^5 pushes down the plunger K^2 against the tension of the spring L^7 . After the valve C^2 has moved to its closed position (shown in Fig. 4) the spring G^6 yields and allows the plunger K^2 to be still further depressed, and when the plunger K^2 reaches its lowest position the spring-catch O engages with the top of the flange K^3 on the plunger K^2 and holds said plunger in its lowest position. When said plunger K^2 is in its lowest position, as shown in Fig. 4, (which is just previous to its rising owing to the piston H^2 moving over and releasing said plunger,) the ports K^4 allow the compressed air passing up through the hollow stem L^3 to pass above the plunger L , and the air-pressure above said plunger forces said plunger down and opens the valve L^4 and allows the air-pressure to pass from the pipe M^2 into the valve-box C and then into the despatch-tube B , driving the carrier, which has just been inserted, to the opposite end of the line and at the same time raising and holding the valve C^2 against its valve-seat A' , as shown in Fig. 4, and upon the removal of the hand from the handle G^4 the plunger K^2 is held down by the spring-catch O and remains in this position, allowing the air to drive the carrier through the despatch-tube until said catch O is removed from the plunger K^3 on the plunger K^2 . The carrier traveling along the tube B toward the left of Fig. 1 to the left terminal, which is identical with that shown at the right of Fig. 1, will pass out through the curved por-

tion and through the opening N' into a suitable receptacle. At this time the piston H^2 has tripped off the spring-catch O , as shown in Fig. 4, and this releasing of the plunger K^2 will move the ports K^4 out of alignment with the chamber K^6 in the upper part of the pocket J , owing to the spring L^7 , and will also bring the upper end of the vertical groove K^5 above the hub K' , and the air in the chamber K^6 will escape through said groove into the casing G^{10} and from thence to the atmosphere, and the parts will assume the position shown in Fig. 3, as heretofore described. With the parts in the position shown in Fig. 3 the air pressure from the pocket M is cut off from the upper part of the pocket J , and a vent is formed by means of the groove K^5 to allow the escape of air from the chamber K^6 through said groove, when the spring L^2 will force the plunger L upwardly, carrying with it the valve L^4 , against its seat, as shown in Fig. 3, closing the opening L^{10} from the pocket M and preventing a further flow of air into the despatch-tube. When the air has thus ceased to flow, the pressure is removed from the valve C^2 , which drops onto its carriage D , and the spring R will move said valve to its normal position, as shown in Fig. 3, and at this time the apparatus is in condition to despatch another carrier.

From the above it is clear that the air in the storage-reservoir M^2 is used only during the transit of the carrier from end to end of the tube, as the pressure is cut off immediately upon the arrival of the carrier at the terminal.

As shown and described, a single tube is used for the transmission of the carrier in both directions, as the terminals and operating parts at both ends may be identical.

The operation above described as taking place in the terminal at the right-hand end of Fig. 1 upon the discharge of a carrier at the left hand of Fig. 1 will likewise occur in the terminal at the left hand of Fig. 1 upon the discharge of a carrier coming from the left hand of Fig. 1 and discharging at the right hand of Fig. 1.

The specific construction of the valve C^2 for closing the despatch-tube B is no part of my present invention, as it forms the subject-matter of another application, filed July 10, 1901, Serial No. 67,753.

I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In an apparatus of the character described, a despatch-tube, a source of compressed air, a valve normally open for closing the despatch-tube after the insertion of the carrier, mechanism for closing said valve, a

valve controlling the supply of compressed air to the despatch-tube, means for holding said valve normally closed, mechanism operated by compressed air for opening said air-
5 supply-controlling valve, means for holding said air-supply-controlling valve open, mechanism operated by compressed air to actuate said valve-holding means to release said air-supply-controlling valve to allow it to close,
10 and means for regulating the movement of said releasing mechanism.

2. In an apparatus of the character described, a despatch-tube, a source of compressed air, a valve normally open for closing
15 the despatch-tube after the insertion of the carrier, mechanism for closing said valve, a valve controlling the supply of compressed air to the despatch-tube, means for holding said valve normally closed, mechanism op-
20 erated by compressed air for opening said air-supply-controlling valve, means for holding said air-supply-controlling valve open, mechanism operated by compressed air to actuate said valve-holding means to release said air-
25 supply-controlling valve to allow it to close, and adjustable means for regulating the movement of said releasing mechanism.

3. In an apparatus of the character described, a despatch-tube, a source of com-
30 pressed air, a valve for closing the despatch-tube after the insertion of the carrier, mechanism for closing said valve, a valve controlling the supply of compressed air to the de-
35 spatch-tube, means for holding said valve nor-
mally closed, mechanism for opening said air-supply-controlling valve, means for holding said air-supply-controlling valve open, a cyl-
40 inder for receiving compressed air when the air-supply-controlling valve is open, a piston
45 movable in said cylinder and provided with a piston-rod extending beyond the cylinder, mechanism for releasing said air-supply-con-
trolling valve to allow it to close and operated by the movement of said piston driven by the
50 compressed air admitted to said cylinder, an opening in said cylinder through which the
air from the cylinder is forced by the move-
55 ment of the piston in one direction to release the air-supply-controlling valve, and an air-
60 inlet valve adapted to open and admit air into the cylinder upon the movement of the piston
65 in the opposite direction upon the closing of the air-supply-controlling valve.

4. In an apparatus of the character de-
55 scribed, a despatch-tube, a source of com-
pressed air, a valve for closing the despatch-
tube after the insertion of the carrier, mech-
anism for closing said valve, a valve control-
60 ling the supply of compressed air to the de-
spatch-tube, means for holding said valve nor-
mally closed, mechanism for opening said air-
supply-controlling valve, means for holding
65 said air-supply-controlling valve open, a cyl-
inder for receiving compressed air when the air-
supply-controlling valve is open, a piston
movable in said cylinder and provided with
a piston-rod extending beyond the cylinder,

mechanism for releasing said air-supply-con-
trolling valve to allow it to close and operated
70 by the movement of said piston driven by the
compressed air admitted to said cylinder, an
opening in said cylinder through which the
air from the cylinder is forced by the move-
75 ment of the piston in one direction to release
the air-supply-controlling valve, means for
adjusting said opening, and an air-inlet valve
adapted to open and admit air into the cylin-
80 der upon the movement of the piston in the
opposite direction upon the closing of the air-
supply-controlling valve.

5. In an apparatus of the character de-
scribed, a despatch-tube, a source of com-
pressed air, a valve normally open for closing
85 the despatch-tube after the insertion of the
carrier, a valve controlling the supply of com-
pressed air, mechanism operated by com-
pressed air for opening said air-supply-con-
trolling valve upon the closing of the de-
90 spatch-tube valve, means for holding said air-
supply-controlling valve open, a cylinder, a
piston in said cylinder operated by com-
pressed air, mechanism operated by the move-
ment of said piston for releasing said air-sup-
95 ply-controlling valve to allow it to close, and
means for regulating the movement of said
piston in said cylinder.

6. In an apparatus of the character de-
scribed, a despatch-tube, a source of com-
pressed air, a valve for closing the despatch-
tube after the insertion of the carrier, a valve
100 controlling the supply of compressed air,
mechanism operated by compressed air for
opening said air-supply-controlling valve, a
catch for holding said air-supply-controlling
105 valve open, a piston operated by compressed
air, mechanism operated by the movement of
said piston for moving said catch to release
said air-supply-controlling valve to allow it
110 to close, and a cylinder in which said piston
is located and provided with an air-vent for
controlling the escape of air in front of the
piston during its movement to release said
air-supply-controlling valve.

7. In an apparatus of the character de-
scribed, a despatch-tube, a source of com-
pressed air, a valve for closing the despatch-
tube after the insertion of the carrier, a valve
115 controlling the supply of compressed air,
mechanism operated by compressed air for
opening said air-supply-controlling valve, a
catch for holding said air-supply-controlling
120 valve open, a piston operated by compressed
air, mechanism operated by the movement of
said piston for moving said catch to release
said air-supply-controlling valve to allow it
125 to close, a cylinder in which said piston is
located and provided with an air-vent for con-
trolling the escape of air in front of the pis-
ton during its movement to release said air-
130 supply-controlling valve, and means for vary-
ing the area of said vent thereby regulating
the movement of said piston.

8. In an apparatus of the character de-
scribed, a despatch-tube, a source of com-

- pressed air, a valve for closing the despatch-tube after the insertion of a carrier, a valve controlling the supply of compressed air, mechanism operated by compressed air for opening said air-supply-controlling valve, a spring-catch for holding said air-supply-controlling valve open, a piston operated by compressed air, mechanism operated by the movement of said piston for moving said spring-
10 catch to release said air-supply-controlling valve to allow it to close, and a cylinder in which said piston is located and provided with an air-vent for controlling the escape of air in front of the piston during its movement to release said air-supply-controlling valve.
15 9. In an apparatus of the character described, a despatch-tube, a source of compressed air, a valve for closing the despatch-tube after the insertion of the carrier, a valve controlling the supply of compressed air, a catch for holding said air-supply-controlling valve open, a piston operated by compressed
20

air, mechanism operated by the movement of said piston for moving said catch to release said air-supply-controlling valve to allow it 25 to close, a cylinder in which said piston is located and provided with an air-vent for controlling the escape of air in front of the piston during its movement to release said air-supply-controlling valve, means for varying 30 the area of said vent thereby regulating the movement of said piston, and an air-inlet valve adapted to open to admit air into said cylinder upon the movement of the piston in the opposite direction upon the closing of 35 said air-supply-controlling valve.

In testimony whereof I have signed my name to this specification, in the presence of two subscribing witnesses, this 17th day of August, A. D. 1900.

MARTIN BARRI.
